UNITED STATES PATENT OFFICE.

CHAUNCEY THOMAS, OF BOSTON, MASSACHUSETTS.

DESIGN FOR A CARRIAGE-SPRING.

SPECIFICATION forming part of Design No. 22,814, dated September 26, 1893.

Application filed July 11, 1893. Serial No. 480,187. Term of patent 14 years.

To all whom it may concern:

Be it known that I, CHAUNCEY THOMAS, a citizen of the United States, residing at Boston, in the county of Suffolk, State of Massachusetts, have invented and produced a new and original Design for Carriage-Springs with Shaft Attachments, of which the following is a specification, reference being had to the accompanying drawing, forming part thereof.

10 The drawing shows a pair of my carriage springs in perspective, and is deemed sufficient to illustrate my design.

15 The leading feature of my design consists in a pair of bow-like springs having shaft attachments.

In said drawing B, B, represent the bow-like springs which have the shaft extension C, said springs being formed as an arc of a

circle and at their forward portions having said shaft extensions; and being arranged with the convex portion downward and with the extremities upward. The bars g, h, extend from one to the other and unite said springs, so as to constitute a carriage body supporting frame.

20 What I claim is—

25 The design for carriage springs herein shown and described, the same comprising the bow-like springs B, B, having the shaft extension, and connected by bars g, h, as set forth.

CHAUNCEY THOMAS.
